UNITED STATES PATENT OFFICE.

SILAS M. WILLIS, OF ATHOL, MASSACHUSETTS.

IMPROVEMENT IN MALLETS.

Specification forming part of Letters Patent No. **140,395**, dated July 1, 1873; application filed March 15, 1873.

To all whom it may concern:

Be it known that I, SILAS M. WILLIS, of Athol, in the county of Worcester and State of Massachusetts, have invented a new and useful Improvement in Mallets; and I do hereby declare the following to be a full, clear, and exact description of the same, reference being had to the accompanying drawings, in which—

Figure 1 is a perspective view of a mallet having my invention. Fig. 2 is a central longitudinal partial section of the same.

My invention consists of an improved mallet having over its face a protecting skin of rawhide, cemented thereto to receive the blow and protect the wooden body from its effects.

That others may fully understand my invention, I will particularly describe it.

A is the body of the mallet, and B is the

handle of the same. C is a skin of rawhide firmly cemented to the face of the body A. Ordinary glue will not answer satisfactorily for this purpose, because its brittleness when thoroughly dry causes the skin to become separated from the wood after a number of blows have been received. I therefore apply the article known as "Chinese cement" mixed with a portion of fish-glue or isinglass.

Having described my invention, what I claim as new is—

A mallet, A, with a skin of rawhide cemented to its face, substantially as set forth.

SILAS M. WILLIS.
